(57) **CLAIM**

The ornamental design for a fishing sinker, as shown.

DESCRIPTION

FIG. 1 is a perspective view of a fishing sinker, showing my design;

FIG. 2 is left side elevation view;

FIG. 3 is a right side elevation view;

FIG. 4 is a front view; and,

FIG. 5 is a back view.

The broken line showing of environment in the drawings is for illustrative purposes only and forms no part of the claimed design.
